CLAIM

The ornamental design for a sensor housing, as shown and described.

DESCRIPTION

FIG. 1 is a front perspective view of a first embodiment of the claimed design for a sensor housing;
FIG. 2 is a front elevation view thereof;
FIG. 3 is a back elevation view thereof;
FIG. 4 is a right side elevation view thereof;
FIG. 5 is a left side elevation view thereof;
FIG. 6 is a top plan view thereof;
FIG. 7 is a bottom plan view thereof;
FIG. 8 is a front perspective view of a second embodiment of the claimed design for a sensor housing;
FIG. 9 is a front elevation view thereof;
FIG. 10 is a back elevation view thereof;
FIG. 11 is a right side elevation view thereof;
FIG. 12 is a left side elevation view thereof;
FIG. 13 is a top plan view thereof; and,
FIG. 14 is a bottom plan view thereof.

The broken lines in the figures illustrate elements of the sensor housing that form no part of the claimed design. The dash-dot lines in the figures illustrate perimeters of the claimed design. The dash-dot lines form no part of the claimed design.

The sensor housing may be arranged along a portion of a vehicle, such as along a roof of the vehicle.

The areas in the embodiment of FIGS. 8-14 shown in a pattern of stipple illustrate areas of contrasting appearance.
